UNITED STATES PATENT OFFICE.

ANNA L. EVANS, OF PRAIRIE VIEW, TEXAS.

MOP.

1,161,644.

Specification of Letters Patent. Patented Nov. 23, 1915.

Application filed March 28, 1914. Serial No. 828,008.

To all whom it may concern:

Be it known that I, ANNA L. EVANS, a citizen of the United States, residing at Prairie View, in the county of Waller and 5 State of Texas, have invented certain new and useful Improvements in Mops, of which the following is a specification.

This invention relates to an improved mop which is intended to be used for washing dishes.

The principal object of the invention is to provide a mop which is so constructed that the cleaning cloth may be removably connected with the handles, the handles affording means for holding the cloth and also 15 affording means for twisting the cloth in order to wring water out of the same.

Another object of the invention is to provide the handles with means for securely 20 but releasably engaging the ends of the cloth.

Another object of the invention is to provide a mop, the handles of which may be very cheaply made, thereby permitting the 25 mop to be placed upon the market at a small cost.

This invention is illustrated in the accompanying drawings wherein—

Figure 1 is a perspective view of the mop; 30 Fig. 2 is a view in elevation looking at the inner face of one of the handles; Fig. 3 is a view showing one of the handles in side elevation with the head broken away to show the hook which engages the cloth; Fig. 4 is an end view of one of the handles.

The handles 10 have their outer end portions provided with openings 11 so that the 40 mop may be hung up or so that if desired a suitable securing device may be passed through the openings 11 to releasably connect the handles. This securing device has not been shown since any suitable means can be used which will permit the handles to be quickly connected and disconnected. Each 45 of the handles is provided at its inner end with a head 12 which is provided with a longitudinally-extending cut-out portion forming a socket 13 leading from the end of the head. The socket 13 is provided with 50 a reduced mouth 14 so that the end of the cloth 15 will be wedged in the sockets 13 and thus prevent their slipping out of engagement with the hook 16. In order to provide

a scraper 17, the outer face of the head 12 is beveled as shown at 18.

When using this mop, the ends of the cloth 15 are forced into the socket 13 and are engaged by the hooks 16. The ends of the cloth expand in the socket 13 and therefore they can not readily slip out of the 60 sockets and become disconnected from the hooks. After the ends of the cloth have been connected with the hooks, the handles are placed together as shown in Fig. 1 and the mop is then ready for use. The cloth is 65 dipped into the water and the dishes can be scrubbed with the mop thus cleaning them. If there are any particles which stick to the dishes, the same may be scraped off by one of the scraping edges 17. If it is desired to 70 wring the water out of the mop during the process of washing the dishes, the handles may be grasped, one with each hand, and then turned to twist the cloth thus wringing the water out of the same. It will therefore be seen that with this mop the handles 75 will afford means for wringing the mop and will also constitute scraping elements. It will be further seen that the cloth may be easily connected and disconnected from the 80 handles and that therefore a new cloth may be easily substituted for the one which has become worn out.

It should also be noted that this mop is very simple in construction and can be easily 85 and cheaply made either from wood, metal, or a suitable composition molded or compressed into shape.

A slide may be provided to close the mouth 14 to securely hold the cloth in 90 the socket 13 and prevent it from being wrenching out through the mouth 14 when wringing the mop.

What is claimed is:

1. A mop comprising handles, each being 95 provided with a head at one end having a longitudinally-extending socket formed therein and provided with a reduced mouth, cloth-engaging means in said socket, and a cloth having its ends fitting into said sockets and removably engaged by said cloth-engaging means.

2. In a mop, a pair of handles, each having one end portion provided with a longitudinally-extending socket having a reduced 105 mouth leading from the inner face of the

handle, and cloth-engaging means mounted in the sockets of said handles.

3. A mop comprising a pair of handles provided with sockets leading from one end, 5 the outer faces of said handles having their end portions cut-out and inclined to form scraping edges, cloth-holding means in said sockets, and a cloth having its ends fitting

into said sockets and releasably engaged by said cloth-engaging means.

In testimony whereof I affix my signature in presence of two witnesses.

ANNA L. EVANS.
